(57) **CLAIM**

The ornamental design for a data storage device, as shown and described.

DESCRIPTION

FIG. 1 is a front, first side, and top isometric view of a data storage device embodying the new design;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof;

FIG. 8 is a first cross-section view thereof along lines 8-8 in FIG. 6; and,

FIG. 9 is a second cross-section view thereof along lines 9-9 in FIG. 6.

The broken lines in the drawings depict portions of the data storage device that form no part of the claimed design.

The pad of a bottom portion of the data storage device may also include different surface contrast, including color contrast, texture contrast, or the like. The top portion of the data storage device may also include different surface contrast, including color contrast, texture contrast, or the like.

Relatively thinner lines are used to illustrate surface shading and form no part of the claimed design.
